HEAT EXCHANGER

Cecil Boling, Brewster, N. Y., assignor to The Heat-X-Changer Co., Inc., Brewster, N. Y., a corporation of New York

Application March 30, 1948, Serial No. 17,899

8 Claims. (Cl. 257—241)

1

This invention relates to the transfer of heat from one fluid to another, and more in particular to highly efficient heat-exchange units and the method of making the same.

An object of this invention is to provide a heat-exchange assembly whereby heat is transferred from one material to another in an extremely efficient and dependable manner. A further object is to provide compact and simple heat-exchange units which are inexpensive to manufacture, sturdy in construction and adaptable to many varied uses. A still further object is to provide heat-exchange units of the above character for heating or cooling one fluid such as a liquid or gas with another without encountering certain of the difficulties of the prior devices. Another object is to provide a method of making heat-exchange units of the above character in a simple manner which is inexpensive and yet thoroughly practical in every respect. These and other objects will be in part obvious and in part pointed out below.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the drawing:

Figure 1 is a side plan view with portions broken away of a heat-exchange unit constituting one embodiment of the invention;

Figure 2 is an enlarged sectional view on the line 2—2 of Figure 1;

Figure 3 is an enlarged sectional view on the line 3—3 of Figure 1 showing only the central portion of the unit; and,

Figure 4 is a top plan view of the unit of Figure 1.

Referring to Figure 1 of the drawing, an elongated cylinder or tube 2 has coiled about it a spiral tube 4 which forms five complete turns between its flared ends 6 and 8. The ends of tube 2 are reduced at 10 and 12, and except for these reduced ends, substantially the entire tube 2 and substantially the entire length of tube 4 are embedded in a cast aluminum block 14, block 14 is cylindrical with two protrusions 16 and 18 at the ends surrounding the portions of tube 4 adjacent ends 6 and 8. As shown best in Figure 2, tube 4 is somewhat oval in cross-section, it having been originally circular in cross-section, and then having been deformed to the oval shape when wound into a spiral.

2

Positioned within tube 2 is a heat-exchange assembly 20 which is formed by a central expanded tube 22 and a fin construction 24. The structure of fin construction 24 is best shown in Figure 3 where it is seen that it is formed from a corrugated sheet of metal bent into cylindrical form. There are 21 flat fin portions or corrugations, and the corrugations originally forming the edges of the sheet are overlapped to form a single fin portion so that there are ten pairs of flat fin portions symmetrically positioned in the annular space between tubes 2 and 22. Each of these flat fin portions is positioned substantially radially with respect to tubes 2 and 22, and in this form they extend tangentially with respect to an imaginary cylinder the diameter of which is approximately one-half the diameter of tube 22.

During manufacture, tube 2 originally has its ends of the same diameter as its main body portion and tube 22 is of slightly smaller diameter than here appears; thus, fin construction 24 and tube 22 are readily positioned within tube 2. The two tubes and the fin construction then are held fixed and tube 22 is expanded to the diameter shown. This expanding is performed by drawing through the tube a cylindrical die of greater diameter than the original internal diameter of tube 22. Thus, tube 22 is expanded so that it continually presses outwardly against each fin portion, and expands the fin construction 24 with considerable force against the inner surface of tube 2. In this way an extremely rigid heat transfer assembly is provided within tube 2, and each of the fin portions is in good heat contacting relationship with tube 2 as well as with tube 22.

After the expanding of tube 22 the ends of tube 2 are reduced and tube 4, which has been wound into a spiral in a mandrel, is slipped into place. The tube assembly thus formed is then positioned within a mold and the block of aluminum is cast around it. The aluminum bonds to the entire embedded surfaces of tubes 2 and 4 and provides excellent heat transfer relationship between the aluminum and each of these tubes. As shown best in Figure 3, tube 4 is in intimate contact with tube 2 and the aluminum fills into the cracks at the edges of tube 4 sufficiently to avoid any cavity. Block 14 not only provides for the even distribution and transfer of heat between tube 2 and tube 4, but the block also provides a heat carry-over so that fluid is cooled evenly in one tube and heated evenly in another tube with out minor fluctuations in temperature in the one

tube affecting the temperature in the other tube. Illustratively, the heat-exchange unit shown in the drawing is for the purpose of cooling liquid refrigerant passing through tube 4 to an evaporator by means of refrigerant gas passing from the evaporator through tube 2. Thus, the liquid refrigerant flowing at a relatively slow rate gives up heat to the walls of tube 4 and this heat passes to tube 2 partly by direct contact with tubes 2 and 4 and partly by indirect transfer through block 14. Furthermore, block 14 has a sufficiently high heat transfer index that there is a tendency for the entire wall of tube 2 to be maintained at substantially the same temperature.

The gas passing through tube 2 is carried in the passageways between the fins of fin construction 24 as well as through tube 22, and there is a minimum resistance to flow. Some of the heat from tube 2 is picked up directly by the refrigerant gas, but the major portion of the heat passes by conduction from tube 2 to the various fin portions with this heat transfer being facilitated by the excellent contact which is provided between tube 2 and the corrugation ridges or fin edges. An additional amount of heat passes from the fin portions to the gas while the remainder of the heat is transferred from the fin to tube 22 and thence to the gas around and mainly within this tube.

In this embodiment tubes 2, 4 and 22 and fin construction 24 are of copper and the passageways for the refrigerant are free of other materials such as solder and the like. This has proved to be of advantage in the adaptation of this invention to certain uses.

As many possible embodiments may be made of the mechanical features of the above invention and as the art herein described might be varied in various parts, all without departing from the scope of the invention; it is to be understood that all matter hereinabove set forth, or shown in the accompanying drawings is to be interpreted as illustrative and not in a limiting sense.

I claim:

1. In heat exchange apparatus of the type wherein a fluid is subjected to a heat transfer operation, the combination of, a pair of concentrically positioned rigid members defining a substantially annular chamber for the flow of the fluid to be subjected to a heat transfer operation, and an annular metallic fin assembly within said chamber and comprising sheet metal corrugations each of which is substantially straight and is non-distortable and extends longitudinally of said chamber bridging the space between said rigid members and is connected to the next adjacent corrugation by a trough-like connecting portion which presents a straight portion in contact with a surface of one of said members, the distance between said rigid members being such that each of said trough-like connecting portions is distorted and each of said trough-like connecting portions is subjected to substantial compressive forces which are applied at the inner and outer peripheries of said fin assembly by said rigid members.

2. In heat exchange apparatus of the type wherein a fluid is subjected to a heat transfer operation, the combination of, a pair of hollow concentrically positioned rigid cylindrical members defining a cylindrical central chamber and an annular chamber both of which chambers are for the flow of fluid to be subjected to a heat transfer operation, and an annular metallic fin

assembly within said annular chamber and comprising sheet metal corrugations each of which is substantially straight and is non-distortable and extends longitudinally of said chamber bridging the space between said rigid members and is connected to the next adjacent corrugation by a trough-like connecting portion which presents a straight portion in contact with a surface of one of said members, the distance between said rigid cylindrical members being such that each of said trough-like connecting portions is distorted and each of said trough-like connecting portions is subjected to substantial compressive forces which are applied at the inner and outer peripheries of said fin assembly by said rigid members.

3. In heat exchange apparatus of the type wherein a fluid is subjected to a heat transfer operation, the combination of, a pair of concentrically positioned rigid cylindrical members defining a substantially annular chamber between the outer surface of the smaller of said members and the inner surface of the larger of said members, said members providing for the flow through said annular chamber of the fluid to be subjected to a heat transfer operation, an annular metallic fin assembly within said chamber and comprising sheet metal corrugations each of which is substantially rectangular and straight and is not distorted and extends longitudinally of said chamber bridging the space between said rigid members and is connected to the next adjacent corrugation by a trough-like connecting portion which presents a straight portion in contact with a surface of one of said cylindrical members, the distance between said cylindrical members being such that each of said trough-like connecting portions is distorted and each of said trough-like connecting portions is subjected to substantial compressive forces which are applied at the inner and outer peripheries of said fin assembly by said cylindrical members, and means exteriorly of the larger of said cylindrical members and providing a passageway for a second fluid and providing for the transfer of heat between fluid flowing through said cylindrical members and said second fluid.

4. In heat exchange apparatus of the type wherein a fluid is subjected to a heat transfer operation, the combination of, a pair of concentrically positioned hollow rigid cylindrical members defining a substantially annular chamber between the outer surface of the smaller of said members and the inner surface of the larger of said members and a cylindrical passageway within the smaller of said members, said members providing for the flow through said annular chamber and said cylindrical passageway of fluid to be subjected to a heat transfer operation, an annular metallic fin assembly within said chamber and comprising sheet metal corrugations each of which is substantially rectangular and straight and is not distorted and extends longitudinally of said chamber bridging the space between said rigid members and is connected to the next adjacent corrugation by a trough-like connecting portion which presents a straight portion in contact with a surface of one of said cylindrical members, the distance between said cylindrical members being such that each of said trough-like connecting portions is distorted and each of said trough-like connecting portions is subjected to substantial compressive forces which are applied at the inner and outer peripheries of said fin assembly by said cylindrical members, and heat transfer means in intimate

contact with the outer surface of the larger of said cylindrical members and providing a passageway for a second fluid and providing for the transfer of heat between fluid flowing through said cylindrical members and said second fluid.

5. In heat exchange apparatus of the type wherein a fluid is subjected to a heat transfer operation, the combination of, a pair of concentrically positioned rigid members defining a substantially annular chamber for the flow of the fluid to be subjected to a heat transfer operation, an annular metallic fin assembly within said chamber and comprising sheet metal corrugations each of which is substantially straight and is non-distortable and extends longitudinally of said chamber bridging the space between said rigid members and is connected to the next adjacent corrugation by a trough-like connecting portion which presents a straight portion in contact with a surface of one of said members, the distance between said rigid members being such that each of said trough-like connecting portions is distorted and each of said trough-like connecting portions is subjected to substantial compressive forces which are applied at the inner and outer peripheries of said fin assembly by said rigid members, a tube formed into a spiral and closely hugging the outer surface of the larger of said rigid members, and a block of aluminum substantially enclosing said larger rigid member and said tube.

6. Apparatus as described in claim 5 wherein said spiral tube is substantially oval in cross-section, and wherein said fin assembly is formed by a single sheet of corrugated metal.

7. Apparatus as described in claim 6 wherein said rigid members are sheet metal cylinders and the larger of said cylinders has its ends reduced in diameter and projecting from said block of aluminum.

8. In heat exchange apparatus of the type wherein a fluid is subjected to a heat transfer operation, the combination of, a pair of concentrically positioned rigid members defining a substantially annular chamber for the flow of the fluid to be subjected to a heat transfer operation, and an annular metallic fin assembly within said chamber and comprising a sheet of metal formed into corrugations each of which is substantially rectangular and straight and is non-distortable and extends longitudinally of said chamber bridging the space between said rigid members, each of said corrugations being connected to the next adjacent corrugation by a trough-like connecting portion which presents a straight portion in contact with a surface of one of said members, the distance between said rigid members being such that each of said trough-like connecting portions is distorted from its original shape and each of said trough-like connecting portions is subjected to substantial compressive forces which are applied at the inner and outer peripheries of said fin assembly by said rigid members.
